GARMENT SUPPORTER

John J. Farrell, Villanova, Pa.

Application January 16, 1932. Serial No. 587,069

8 Claims. (Cl. 24—245)

My invention relates to garment supporters of the type which is adapted to clamp between two clamping members a portion of the material of the garment to be supported, and my invention 5 relates particularly to improvements on the garment supporter of my application for patent, Serial No. 531,765, filed April 2, 1931; patented February 16, 1932, as No. 1,845,255, the improvements relating particularly to the cushion member of 10 the gripping device, and the means for holding it and to the construction of the strap openings by which it is made possible to insert or remove a closed loop strap.

With the above indicated objects, and other 15 objects hereinafter disclosed, in view, my invention consists in the construction and combination of elements hereinafter described and claimed.

Referring to the drawing:

Figure 1 is a central longitudinal sectional view on an enlarged scale of a complete garment supporter embodying my invention.

Figure 2 is a front view, and Figure 3 is a side view, actual size, of the device shown in Figure 1, the connecting strap being omitted.

Figure 4 is a front view and Figure 5 is a side view of the outer member of the supporter, and

Figure 6 is a front view and Figure 7 is a side view of the inner member of the supporter.

In the drawing, as in my application No. 531,765, above referred to, 1 and 2 indicate respectively the inner and outer members of the garment supporter between which the material of the stocking or other garment to be supported is held, the back member 1 being the one which is, in use, next to the limb of the wearer. These members, 1 and 2, are each cut or stamped from sheet metal in the shapes shown in Figures 6 and 7, and Figures 4 and 5.

Inner member 1 has at its upper end a strap opening or slot 3 and has at its lower end a strap opening 4 for connecting strap 30. Outer member 2 has at its upper end a relatively long slot 5 of such length as may be required to receive 45 the broad band usually employed to connect the garment supporter to the waist band, corset or other garment of the wearer.

Inner member 1 has formed in it an upper opening 6 and a lower opening 7. The strap opening 3 is continuous with upper opening 6. The cross bar 8 at the upper edge of strap opening 3 has midway between its ends an opening 9 of sufficient width to permit the strap 30, which connects the members 1 and 2 loosely together, 55 to be inserted edgewise through it.

A part of the sheet material from upper opening 6 extending upward from the lower edge of the opening is bent forward and downward to form a curved tongue 10. A part of the material 60 from lower opening 7 extending upward from

bar 11 which forms its lower edge is bent forward and downward to form curved tongue 12. From the lower edge of bar 11 a tongue 13 extends downward carrying cross bar 14 which forms the upper edge of strap opening 4. The lower edge of this opening is formed by cross bar 15 which has midway between its ends an opening 16 adapted to permit the strap 30 to be passed edgewise through it.

The bar 17 at the upper edge of slot 5 of outer member 2 is preferably cut also, and bar 18 at the lower edge of this slot has an opening 19 at its centre of sufficient width to permit the connecting strap 30 to be inserted endwise through it. This bar 18 forms the upper edge of an opening 20 having at its lower edge cross bar 21. Extending downward from the lower edge of cross bar 21 is an opening 22 of sufficient extent to permit tongue 10 to pass through it so as to permit the upper surface of this tongue to engage the lower edge of cross bar 21.

Outer member 2 has in its lower opening 23 formed between left hand leg 24 and right hand leg 25, which extend downward as shown in Figure 4. From the lower end of leg 24 cross bar 26 extends to the lower end of leg 25 with its end preferably extending into a recess 27 therein.

On cross bar 26 is carried cushioning material adapted to fit within the under face of tongue 12 of inner member 1. This cushioning material is preferably a piece of tubing 28, of rubber or other elastic material, the opening in which is adapted to fit on cross bar 26, onto which it may be slipped by springing the end of the cross bar out of recess 27, slipping the tubing onto it and returning the end of the cross bar back into recess 27.

The cross bar 26 is so located with reference to cross bar 21 that when the elastic tubing 28, with the material of a stocking or other garment drawn forward over it, is brought into engagement with the under face of curved tongue 12 and the upper portion of outer member 2 is pressed towards the inner member, tongue 10 will engage cross bar 21 and lock the two members together.

To unlock the two members it is only necessary to press tongue 10 rearward to disengage it from cross bar 21.

The connecting strap 30 is run through strap opening 4 in the lower end of inner member 1, then along the back of this member 1, through strap opening 3, through strap opening 5 in outer member 2, back over bar 18 and down the back member 1 to its lower end. As the openings in cross bars 8, 18, and 15 permit the strap to be inserted edgewise, the ends of the strap may be sewed together before it is applied to the members 1 and 2. The strap hinges the members at

their upper ends leaving the lower ends free to swing from and towards each other and the double thickness at the back of the inner member serves to protect the wearer from direct contact 5 with the metal of the inner member as well as to serve as a cushion.

Having thus described my invention, what I claim is:—

1. In a garment supporting member a gripping device comprising an outer and an inner member provided near their lower ends with co-operating means for clamping the material of a garment between them, the outer member having a strap opening near its upper end, the inner 15 member having a strap opening near its upper end and a strap opening at its lower end, and means for holding the clamping means of the two members in clamping position, and a connecting strap extending through the strap openings at the upper ends of both members, passing 20 along the back of the inner member and through the strap opening at its lower end.

2. In a garment supporting member a gripping device comprising an outer and an inner member provided near their lower ends with co-operating means for clamping the material of a garment between them, the outer member having a strap opening near its upper end, the inner member having a strap opening near 25 its upper end and a strap opening at its lower end and means for holding the clamping means of the two members in clamping position, and a connecting strap extending through the strap openings at the upper ends of both members, passing along the back of the inner member and through the strap opening at its lower end, and back along the back of the inner member to its upper end forming a closed loop 30 with two thicknesses of material at the back of the inner member.

3. In a garment supporter a gripping device comprising an outer member, having a strap opening near its upper end, an inner member having a strap opening near its upper end, the outer member being provided near its lower end with a device adapted to engage the material of the garment to be supported, and having near its upper end a cross bar, and the inner member being provided near its lower end with an outwardly and downwardly extending tongue adapted to embrace the upper end of the upwardly extending device carried by the outer member to clamp the material thereon, said inner member having near its upper end locking means adapted 45 to engage the underside of the cross bar of the outer member to lock the inner and outer members against movement, and means for connecting the outer and inner members comprising a flexible strap extending through the strap openings at the upper ends of the members.

4. In a garment supporter a gripping device comprising an outer member having a strap opening near its upper end, a cross-bar forming one edge of said opening having an opening midway 50 between its ends adapted to permit a strap to be passed edgewise through it, an inner member also having a strap opening near its upper end, the outer member being provided near its lower end with a device adapted to engage the material of the garment to be supported, and having near its upper end a cross bar, and the inner member being provided near its lower end with an outwardly

and downwardly extending tongue adapted to embrace the upper end of the upwardly extending device carried by the outer member and having near its upper end locking means adapted to engage the underside of the cross bar of the outer member, means for connecting the members at their upper ends comprising a flexible strap extending through the strap openings. 80

5. In a garment supporter a gripping device comprising an outer member, an inner member loosely connected at its upper end to the outer member, the outer member being provided near its lower end with means for holding a cushion in the form of a tube of elastic material, comprising oppositely arranged downwardly extending legs, one of them provided with a cross bar carrying a tube of elastic material, said cross bar extending toward and having locking engagement with the other leg and the inner member being provided with an outwardly and downwardly extending tongue adapted to embrace the upper end of the cushion. 85

6. In a garment a gripping device comprising an outer member, an inner member loosely connected at its upper end to the outer member, the outer member being provided near its lower end with downwardly extending legs, a cross bar permanently connected at one of its ends to one of said legs, said cross bar carrying a cushion in the form of a tube of elastic material, said cross bar 90 extending toward the other leg, said other leg having opposite the said cross bar a recess adapted to receive its free end, and the inner member being provided with an outwardly and downwardly extending tongue adapted to embrace the upper end of the cushion. 95

7. In a garment supporter a gripping device comprising an outer member, an inner member loosely connected at its upper end to the outer member, the outer member being provided near its lower end with downwardly extending legs, a cross bar permanently connected at one of its ends to one of said legs, said cross bar carrying a cushion in the form of a tube of elastic material, means carried by the other leg for engaging 100 the free end of the cross bar, and the inner member being provided with an outwardly and downwardly extending tongue adapted to embrace the upper end of the cushion. 105

7. In a garment supporter a gripping device comprising an outer member, an inner member loosely connected at its upper end to the outer member, the outer member being provided near its lower end with downwardly extending legs, a cross bar permanently connected at one of its ends to one of said legs, said cross bar carrying a cushion in the form of a tube of elastic material, means carried by the other leg for engaging 110 the free end of the cross bar, and the inner member being provided with an outwardly and downwardly extending tongue adapted to embrace the upper end of the cushion. 115

8. In a garment supporter a gripping device

comprising an outer member, having a strap opening near its upper end, an inner member having a strap opening near its upper end and a strap opening at its lower end, the outer member being provided near its lower end with means for holding a cushion, a cushion having a portion thereof extending upwardly with respect to the lower end of the supporter, said cushion being carried by said holding means, the inner member being provided with an outwardly and downwardly ex-
